STRINGED MUSICAL INSTRUMENT

Filed July 9, 1942

UNITED STATES PATENT OFFICE

2,335,244

STRINGED MUSICAL INSTRUMENT

Carmelo Gugino, Buffalo, N. Y.

Application July 9, 1942, Serial No. 450,235

3 Claims. (Cl. 84—293)

This invention relates to a stringed musical instrument and more particularly to a stringed musical instrument of the guitar or mandolin type in which the construction is composed of a sound box, a neck and strings which are under relatively great tension and which terminate at the extremities of the neck and the sound box.

This application is an improvement on the construction described and claimed in my patent for Stringed musical instrument No. 2,113,446, issued April 5, 1938.

With instruments such as guitars where a relatively large number of strings are employed and where the strings are under a comparatively high tension, the tension of the strings tends to bend the neck upwardly and to permanently distort it and the sound box. As this occurs the strings gradually move away from the fingerboard and render the instrument more and more difficult to play since the player is required to use a great deal more finger pressure in fingering the strings and also is required to move them a greater distance to engage the frets of the fingerboard. The tonal qualities of the instrument are also adversely affected by the distortion of the instrument and with the abnormally high strings it is impossible to finger the instrument expertly. In addition to this, the accuracy of each individual note played upon the strings is impaired due to the fact that each string is put under excessive tension and its pitch thereby considerably changed when the player moves the string downwardly an excessive distance into contact with the desired fret.

It is one of the objects of this invention to provide a musical instrument of the guitar type in which the strings are connected at their opposite ends to a string carrying member which extends the full length of the neck and sound box and to which the sound box is separately connected, the strings having no direct connection with the sound box and the string carrying member being sufficiently rigid to adequately resist the tendency of the strings to distort the neck.

Another object is to provide an instrument in which the distance of the frets from the strings can readily be adjusted so that the player can adapt the instrument to his own fingering technique.

Another object of the invention is to provide such a construction in which the string carrying member supports the strings at the usual distance from the sound board of the sound box, this sound board being centrally grooved in its

upper face to receive the string carrying member in recessed relation to the sound box.

It is another object of the invention to provide such a structure in which the string carrying member is constructed of wood thereby to overcome the prejudice of some musicians to the use of metal adjacent the sound box and also to permit of following conventional practice in ornamenting the instrument and render it substantially similar in appearance to conventional instruments as now manufactured.

Another object of the invention is to provide such a structure in which the neck portion of the string carrying member can be adjusted so as to straighten the neck if the neck has become bowed upwardly due to the tension of the strings, the string carrying member being internally provided with a straightening rod which is so arranged therein that upon adjusting the tension in this rod the neck of the instrument can be restored to its straightened condition.

Another object of the invention is to provide such an instrument which is prevented from sliding along the player's knee when the instrument is being played. For this purpose the side of the sound box which rests on the player's knee is cut out to provide a knee-grip which prevents the instrument from sliding.

In the accompanying drawing:

30 Fig. 1 is a top plan view of a guitar made in accordance with my invention.

Fig. 2 is a vertical, central, longitudinal section therethrough.

Figs. 3, 4 and 5 are enlarged, fragmentary sections, taken on the correspondingly numbered lines in Fig. 2.

Fig. 6 is a plan view of the bottom of the string carrying member.

Fig. 7 is a top plan view of a conventional shape of guitar embodying a modified form of my invention.

Fig. 8 is a side view thereof.

Fig. 9 is a fragmentary, vertical, longitudinal central section through the modified form of the invention shown in Fig. 7, this section being taken on line 9—9, Fig. 7.

Fig. 10 is a fragmentary, transverse section, taken on line 10—10, Fig. 7.

Fig. 11 is a fragmentary side elevation, similar to Fig. 8 and showing a still further modified form of the invention.

Referring to the form of the invention shown in Figs. 1—6, the invention is shown as embodied in a guitar, the sound box 10 of which comprises a sounding board 11 and side walls 12 connecting

this sounding board with the back 13 of the sound box. As best shown in Fig. 4, the sounding board 11 is formed to provide a central longitudinal groove 14 of substantial depth in its upper face, a part of the string carrying member being set into this groove, as hereinafter described. The groove 14 is provided by cutting out a long, narrow slot in the sounding board 11 which slot extends longitudinally the full length of the sound box 10. To the underside of each of the opposite edges of this slot a side wall 15 of suitable material is secured, these side walls being shown as extending longitudinally of the said slot substantially the full length thereof. The side walls 15 are shown as being thicker than the sounding board 11 and the opening provided by these side walls is closed by an auxiliary section of sounding board 16 secured to the lower ends of these side walls.

In order to improve the tonal quality of the instrument, the sounding board 11 is provided at one side only with a sound opening 16. I have found that the degree to which the sounding board is perforated with sound openings has a pronounced effect on the tonal qualities of the instrument and that the fewer sound openings employed the greater the quality of the instrument. With this in view, instead of providing the sounding board with the conventional pair of sound openings, one on each side of the strings, I leave the sounding board at one side of the strings imperforate and provide only one sound opening 16 at the opposite side of the strings.

A string carrying member, indicated generally at 20, is disposed within the groove 14 and is formed to provide an integral neck portion 21, the underside of which is rounded to the conventional shape of a guitar neck. The forward end of the neck portion 21 is broadened and flattened to provide the key carrying head 22 which, as shown in Fig. 2, extends forwardly and downwardly from the neck portion 21. The underside of the neck portion 21 at its rear end is provided with a downward extension 23 having a rear vertical transverse face 24. The upper flat face 25 of the neck extends rearwardly past the downward extension 23 to a point 26 where this upper face is stepped down. The face 25 is provided with the usual frets 27 over which the strings 28 extend. That portion of the string carrying member, indicated generally at 30, which extends rearwardly from the neck of the instrument is preferably T-shaped in cross section, as best illustrated in Fig. 4, and forms a compression part. Starting at the step 26 a flat upper face 31 is provided by the laterally extending flanges 32 of the T-shaped compression part 30, the face 31 extending rearwardly to the extreme rear end of the sound box 10 and this face also being preferably slightly curved downwardly toward the rear end of the sound box so as to conform to the contour of the upper face of the sounding board 11. The outer ends of the flanges 32 do not extend laterally as far as the broader upper flat face 25 of the neck 21. A vertical reenforcing rib 33 is formed on the underside of the flanges 32 and forms the vertical leg of the T-shaped portion 30 and this rib extends into and substantially fills the groove 14 provided in the sounding board, as best shown in Fig. 4. The sides of this rib 33 gradually become smaller in vertical extent from the step 26 toward the rear vertical face 24 and immediately in rear of this rear vertical face 24 the rib 33 is formed to extend laterally from each side thereof to provide a pair of locking lugs 34, 35 and

a pair of notches 35, 35, as best shown in Fig. 3.

It is to be understood that the string carrying member is carved or otherwise suitably formed as an integral or one-piece structure from any suitable material such as a type of wood adapted for use in musical instruments of this character. It will also be noted that the upper face 25 of the neck 21, as does the neck itself, gradually tapers downwardly toward its forward end and is slightly angularly formed with respect to the upper face 31 of the T-shaped portion 30, as best shown in Fig. 2. Also, the key carrying head 22 at the forward end of the neck 21 inclines downwardly relative to the axis of the neck.

The string carrying member 20 throughout its entire length is centrally provided with a bore 36 which is adapted to receive a flexible straightening rod 37 which is externally threaded at its opposite ends so as to receive the nuts 38 and 39 at the front and rear ends thereof, respectively. The front nut 38 is preferably knurled so as to facilitate its manual adjustment.

The extreme rear end of the string carrying member is secured to the sound box 10 in any suitable manner and as best shown in Fig. 5 is screwed by means of a pair of transversely spaced screws 45 to a rear reenforcing block 46 which is centrally provided on the inside of the sound box 10 at the rear end thereof. A front reenforcing block 47 is also provided at the front end of the sound box and as best shown in Fig. 3 is provided with an inverted T-shaped slot 48 which is adapted to receive the locking lugs 34. In this manner the string carrying member can be securely attached to the sound box 10 by sliding the rear end of this string carrying member along the groove 14 until the lugs 34 engage the slot 48 and the rear vertical face 24 abuts against the front outer face of the sound box, as best shown in Fig. 2, this providing a dove-tailed form of interlocking engagement, and the rear end of the string carrying member is secured to the extreme rear end of the sound box by the screws 45. As shown in Fig. 3 the notches 35 receive the inner opposing edges of the slotted sounding board 11 and the opposing flanges 49 formed by the inverted T-shaped slot 48 provided in the front reenforcing block 47. The strings 28 rest on a bridge 55 which straddles the T-shaped portion 30 of the string carrying member 20 and the legs of which bear against the upper face of the sounding board 11 in the usual manner. It is desirable that the bridge be at all times out of contact with the string carrying member, the vibrations of the strings being conducted directly to the sounding board without any interference by the T-shaped portion 30 of the string carrying member.

As shown in Fig. 2 the strings are at a uniform distance above the upper flat face 25 of the neck 21 so that the same amount of finger pressure is required at any point along the face 25 thereby to provide a uniform playing condition. The extreme rear ends of the strings 28 are anchored in the usual cross bar 56 which in turn is connected by a U-shaped link 57 with a strap 58. This strap extends over the extreme rear corner of the T-shaped portion 30 of the string carrying structure so that substantially all of the tension of the strings is borne by the string carrying member. The strap 58 is anchored to the rear end of the string carrying member by having the rear end of the straightening rod 37 passing through an opening provided in the strap and securely held in place by the nut 39.

The key carrying head 22 carries in holes provided therein a plurality of the usual adjustable keys 60 in spaced relation to one another and the extreme front ends of the strings 28 are suitably fastened to these keys.

If the neck of the instrument becomes bowed upwardly due to the tension of the strings, the nut 38 can be adjusted by tightening the same so as to straighten out the neck and restore it to its normal position.

In order to prevent the instrument when held in its playing position from sliding along or off the player's knee, the sound box is formed as follows:

That side of the sound box which rests upon the knee of the player is cut out or recessed to a substantial extent to provide a recess 65 of substantial depth, the portion of the sound box immediately adjacent the forward end of this recess being extended outwardly, as indicated at 66, to provide a hook or grip which conforms to the knee of the player and prevents the instrument from sliding off the knee. To further facilitate accommodation of the fingering hand of the player when fingering the higher section of the face 25, the forward wall of the sound box on the same side of the sound box in which the knee-grip is provided is cut back, as indicated at 67, to permit of greater reach.

In Figs. 7-10 is illustrated a guitar embodying a modified form of means for adjusting the distance of the strings from the frets on the neck so that the player can adjust this distance to obtain any desired resistance of the strings to the fingering and thereby adapt the instrument to such finger pressure as best suits his technique. The guitar is shown as having a sound box 68 of conventional shape, the sounding board 69 having, however, only one sound opening at one side with the other side imperforate as with the form of the invention shown in Figs. 1-6. As with the form of the invention shown in Figs. 1-6, a flexible straightening rod 70 is arranged in a bore provided centrally in the neck 71 and key carrying head 72, the rear end of this rod being suitably anchored in the rear extremity of the neck 71 and the front end of this straightening rod being exteriorly threaded and carrying a manual adjusting nut 74 which can be tightened in the same manner in which the adjusting nut 38 in the form of the invention illustrated in Figs. 1-6 is adjusted in order to straighten out the neck and thereby restore it to its normal and proper condition. As with the form of the invention shown in Figs. 1-6, it will be seen that this straightening rod extends from one extremity of the neck structure to the other.

In the form of the invention shown in Figs. 7-10, the sound box is provided at its front end with a reenforcing block 75 and this block and the overlying part of the sounding board 69 are provided with a horizontal T-shaped groove or slot 76, this slot extending rearwardly from the front end of the sound box. In the sounding board, this slot 76 is carried rearwardly to a cross bar 78 under the sounding board and under this rearward extension of the slot 76, the reenforcing block 75 is stepped downwardly, as indicated at 79 in Fig. 9. The neck 71 is provided at its rear end with a downward extension 80 which fits into the upper part of the T-shaped slot 76 and extends into the sound box above the stepped portion 79 of the reenforcing block 75. This portion 80 of the neck carries a plate 82 the sides of which extend beyond the neck and fit in the

broad lower part of the T-shaped slot 76. This plate may be fastened to the underside of the neck by screws 83 and since the T-shaped slot 76 extends to the front extremity of the sound box, it will be seen that the neck assembly can be slipped endwise into this slot from the front end of the sound box and upon stringing the instrument, the sound box and neck are held together by the strings. The fit of the neck and plate 82 in the T-shaped slot 76 is sufficiently loose that the neck is free to pivot slightly about the outer upper corner 84 of the reenforcing block 75, this pivotal mounting for the neck forming an important feature of the invention.

At its inner extremity, immediately above the step 79 of the reenforcing block 75, the neck is provided on its underside with a push plate 85. Below this push plate a plate 86 is secured to the step 79 of the reenforcing block, this plate 86 having a threaded opening receiving a vertical screw 87, the upper end of which bears against the push plate 85 and the lower end of which extends through the back of the sound box so as to be accessible from the exterior of the sound box. This exposed end of the screw 87 is shown as slotted so as to be capable of being turned by a screw driver.

It will be seen that upon screwing the screw 87 in, the inwardly projecting end of the neck is moved upwardly and the entire neck structure is pivoted around the corner 84 of the reenforcing block 75. This brings the strings closer to the frets on the neck so that the strings are pressed against the frets with greater ease. The strings are thereby also brought into closer parallelism with the upper surface of the neck.

It is apparent that the sliding connection between the neck and the sound box with the neck pivoting around the corner 84 could be substituted by an actual pivotal connection. Such a modification is illustrated in Fig. 11 in which the sound box 90 is connected with the neck 91 by a hinge 92, the adjustment being achieved by a screw mounted similarly to the screw 87 in the form of the invention shown in Figs. 7-10.

From the foregoing and with reference to the form of the invention illustrated in Figs. 1-6, it will be seen that the present invention provides a very simple, attractive and rigid means for securing the strings of a musical instrument, such as a guitar, to a string carrying member to which the sound box is substantially independently secured, the sound box being thereby free from the liability of becoming distorted due to the heavy strains imposed by the numerous strings and the string carrying structure being sufficiently rigid to adequately withstand these strains. At the same time the use of metal over the sounding board is avoided and by recessing the string carrying member into a groove provided in the sounding board a compression bar of greater cross sectional dimensions can be employed without raising the strings unduly high or without noticeably departing from conventional practice in the manufacture of guitars. It will further be seen that both forms of the invention provide a very simple and effective way of restoring a distorted neck back to its normal position by employing a straightening rod, the tension in which can be very readily adjusted by tightening a nut at one end of the instrument, this rod being concealed within the string carrying member. Further, the provision of the knee-grip on the side of the sound box has the very desired advantage of pre-

venting the instrument for sliding off the knee of the player. It will also be seen that a guitar having the advantages of the invention can be produced at a price not substantially greater than the cost of standard instruments. It will also be seen that the pivotal mounting of the neck in combination with the adjusting screw in the sound box, as shown in Figs. 7-11, provides a very simple and effective means for raising or lowering the strings relative to the frets thereby to adapt the fingering of the instrument to the touch of the player.

I claim as my invention:

1. A stringed musical instrument, comprising a sound box having a sounding board and an internal reenforcing block at one end, a neck pivotally connected to said one end of said sound box to swing transversely of said sounding board and having an end projecting into said sound box above said reenforcing block, a bridge on said sounding board, strings connected adjacent the opposite extremities of said sound box and neck and bearing against said bridge, and an adjusting screw interposed between said reenforcing block and said projecting end of said neck and having threaded engagement with one to hold said neck in different positions about its pivotal connection with said sound box, the end of said screw being accessible from the exterior of said sound box.

2. A stringed musical instrument, comprising a sound box having a sounding board and an internal reenforcing block at one end, a neck pivotally connected to said one end of said sound

box to swing transversely of said sounding board and having an end projecting into said sound box above said reenforcing block, a bridge on said sounding board, strings connected adjacent the opposite extremities of said sound box and neck and bearing against said bridge, and an adjusting screw interposed between said reenforcing block and said projecting end of said neck and having threaded engagement with one to hold said neck in different positions about its pivotal connection with said sound box, the end of said screw being accessible from the exterior of said sound box.

3. A stringed musical instrument, comprising a sound box having a sounding board and an internal reenforcing block at one end, the sounding board and said reenforcing block being provided with a horizontal T-slot extending inwardly from said one end of said sound box, a neck having one end fitting in said T-shaped slot and projecting into said sound box, said neck pivoting transversely of said sounding board about the outer horizontal corner of said reenforcing block, a bridge on said sound box, strings connected adjacent the opposite extremities of said sound box and neck and bearing against said bridge, and a vertical adjusting screw interposed between said reenforcing block and said projecting end of said neck and having threaded engagement with one to hold said neck in different positions about its pivotal connection with said reenforcing block, the end of said screw being accessible from the exterior of said sound box.

CARMELO GUGINO.
